US0D1058999S

(12) **United States Design Patent** (10) Patent No.: **US D1,058,999 S**
(45) Date of Patent: ** Jan. 28, 2025

(54) TODDLER SHOE WITH STRAP AND HEEL PULL	D150,729 S 8/1948 Sandler
(71) Applicant: Gavrieli Brands LLC , Beverly Hills, CA (US)	D151,099 S 9/1948 Strauss
(72) Inventor: Kfir Gavrieli , Beverly Hills, CA (US)	D151,685 S 11/1948 Eberle et al.
(73) Assignee: Gavrieli Brands LLC , Beverly Hills, CA (US)	D166,090 S 3/1952 Maling
(**) Term: 15 Years	2,772,488 A 12/1956 Meltzer
(21) Appl. No.: 29/733,119	2,904,814 A 9/1959 Scholl
(22) Filed: Apr. 29, 2020	3,148,378 A 9/1964 Tibbitts
(51) LOC (15) Cl. 02-04	D200,897 S 4/1965 Mitchell
(52) U.S. Cl. USPC D2/900	D220,464 S 4/1971 Hayoshi

CLAIM

The ornamental design for a toddler shoe with strap and heel pull as shown and described.

DESCRIPTION

The file of this patent contains at least one drawing executed in color. Copies of this patent with color drawing(s) will be provided by the Office upon request and payment of the necessary fee.

FIG. 1 is a perspective view of an embodiment of my new design of a toddler shoe with strap and heel pull;
 FIG. 2 is a first side view of the design of FIG. 1;
 FIG. 3 is a second side view of the design of FIG. 1;
 FIG. 4 is a top view of the design of FIG. 1;
 FIG. 5 is a bottom view of the design of FIG. 1;
 FIG. 6 is a front view of the design of FIG. 1;
 FIG. 7 is a back view of the design of FIG. 1;
 FIG. 8 is a perspective view of another embodiment of my new design of a toddler shoe with strap and heel pull, in which the outpatch soles are hatched using the USPTO convention of solid diagonal lines extending from the upper left to the lower right for green (Pantone 315 or Pantone 316, any one of Pantone 321-Pantone 324, any one of Pantone 327-Pantone 378, any one of Pantone 381-Pantone 385, any one of Pantone 389-Pantone 392, any one of Pantone 553-Pantone 584, any one of Pantone 621-Pantone 627, Pantone 802, any one of Pantone 3285-Pantone 3435, any one of Pantone 5463-Pantone 5747, any one of Pantone 7478-Pantone 7498, or any one of RAL 6000-RAL 6038);
 FIG. 9 is a first side view of the design of FIG. 8;
 FIG. 10 is a second side view of the design of FIG. 8;
 FIG. 11 is a top view of the design of FIG. 8;
 FIG. 12 is a bottom view of the design of FIG. 8;
 FIG. 13 is a front view of the design of FIG. 8;
 FIG. 14 is a back view of the design of FIG. 8;
 FIG. 15 is a perspective view of another embodiment of my new design of a toddler shoe with strap and heel pull;
 FIG. 16 is a first side view of the design of FIG. 15;
 FIG. 17 is a second side view of the design of FIG. 15;
 FIG. 18 is a top view of the design of FIG. 15;
 FIG. 19 is a bottom view of the design of FIG. 15;
 FIG. 20 is a front view of the design of FIG. 15;
 FIG. 21 is a back view of the design of FIG. 15;
 FIG. 22 is a perspective view of another embodiment of my new design of a toddler shoe with strap and heel pull;
 FIG. 23 is a first side view of the design of FIG. 22;
 FIG. 24 is a second side view of the design of FIG. 22;
 FIG. 25 is a top view of the design of FIG. 22;
 FIG. 26 is a bottom view of the design of FIG. 22;
 FIG. 27 is a front view of the design of FIG. 22;
 FIG. 28 is a back view of the design of FIG. 22;
 FIG. 29 is a perspective view of another embodiment of my new design of a toddler shoe with strap and heel pull;
 FIG. 30 is a first side view of the design of FIG. 29;
 FIG. 31 is a second side view of the design of FIG. 29;
 FIG. 32 is a top view of the design of FIG. 29;
 FIG. 33 is a bottom view of the design of FIG. 29;
 FIG. 34 is a front view of the design of FIG. 29;
 FIG. 35 is a back view of the design of FIG. 29;
 FIG. 36 is a perspective view of another embodiment of my new design of a toddler shoe with strap and heel pull;

FIG. 37 is a first side view of the design of FIG. 36;
FIG. 38 is a second side view of the design of FIG. 36;
FIG. 39 is a top view of the design of FIG. 36;
FIG. 40 is a bottom view of the design of FIG. 36;
FIG. 41 is a front view of the design of FIG. 36;
FIG. 42 is a back view of the design of FIG. 36;
FIG. 43 is a perspective view of another embodiment of my new design of a toddler shoe with strap and heel pull;
FIG. 44 is a first side view of the design of FIG. 43;
FIG. 45 is a second side view of the design of FIG. 43;
FIG. 46 is a top view of the design of FIG. 43;
FIG. 47 is a bottom view of the design of FIG. 43;
FIG. 48 is a front view of the design of FIG. 43;
FIG. 49 is a back view of the design of FIG. 43;
FIG. 50 is a perspective view of another embodiment of my new design of a toddler shoe with strap and heel pull, in which the outpatch soles are hatched using the USPTO convention of diagonal cross-hatched lines for orange (Pantone 148-Pantone 154, any one of Pantone 156-Pantone 168, any one of Pantone 172-Pantone 175, any one of Pantone 470-Pantone 475, any one of Pantone 486-Pantone 489, any one of Pantone 712-Pantone 721, Pantone 804, Pantone 811, any one of Pantone 1205-Pantone 1685; or any one of RAL 2000-RAL 2013);
FIG. 51 is a first side view of the design of FIG. 50;
FIG. 52 is a second side view of the design of FIG. 50;
FIG. 53 is a top view of the design of FIG. 50;
FIG. 54 is a bottom view of the design of FIG. 50;
FIG. 55 is a front view of the design of FIG. 50;
FIG. 56 is a back view of the design of FIG. 50;
FIG. 57 is a perspective view of another embodiment of my new design of a toddler shoe with strap and heel pull;
FIG. 58 is a first side view of the design of FIG. 57;
FIG. 59 is a second side view of the design of FIG. 57;
FIG. 60 is a top view of the design of FIG. 57;
FIG. 61 is a bottom view of the design of FIG. 57;
FIG. 62 is a front view of the design of FIG. 57;
FIG. 63 is a back view of the design of FIG. 57;
FIG. 64 is a perspective view of another embodiment of my new design of a toddler shoe with strap and heel pull;
FIG. 65 is a first side view of the design of FIG. 64;
FIG. 66 is a second side view of the design of FIG. 64;
FIG. 67 is a top view of the design of FIG. 64;
FIG. 68 is a bottom view of the design of FIG. 64;
FIG. 69 is a front view of the design of FIG. 64;
FIG. 70 is a back view of the design of FIG. 64;
FIG. 71 is a perspective view of another embodiment of my new design of a toddler shoe with strap and heel pull;
FIG. 72 is a first side view of the design of FIG. 71;
FIG. 73 is a second side view of the design of FIG. 71;

FIG. 90 is a front view of the design of FIG. 85;
FIG. 91 is a back view of the design of FIG. 85;
FIG. 92 is a perspective view of another embodiment of my new design of a toddler shoe with strap and heel pull, in which the outpatch soles are hatched using the USPTO convention of dashed vertical lines for purple or violet (Pantone 228-Pantone 275, any one of Pantone 511-Pantone 531, any one of Pantone 663-Pantone 669, any one of Pantone 681-Pantone 690, Pantone 807, Pantone 813 or Pantone 814, any one of Pantone 2395-Pantone 2695, Pantone 2715, Pantone 2725, any one of Pantone 2735-Pantone 2746, any one of Pantone 5115-Pantone 5315, or any one of RAL 4001-RAL 4012);
FIG. 93 is a first side view of the design of FIG. 92;
FIG. 94 is a second side view of the design of FIG. 92;
FIG. 95 is a top view of the design of FIG. 92;
FIG. 96 is a bottom view of the design of FIG. 92;
FIG. 97 is a front view of the design of FIG. 92;
FIG. 98 is a back view of the design of FIG. 92;
FIG. 99 is a perspective view of another embodiment of my new design of a toddler shoe with strap and heel pull;
FIG. 100 is a first side view of the design of FIG. 99;
FIG. 101 is a second side view of the design of FIG. 99;
FIG. 102 is a top view of the design of FIG. 99;
FIG. 103 is a bottom view of the design of FIG. 99;
FIG. 104 is a front view of the design of FIG. 99;
FIG. 105 is a back view of the design of FIG. 99;
FIG. 106 is a perspective view of another embodiment of my new design of a toddler shoe with strap and heel pull;
FIG. 107 is a first side view of the design of FIG. 106;
FIG. 108 is a second side view of the design of FIG. 106;
FIG. 109 is a top view of the design of FIG. 106;
FIG. 110 is a bottom view of the design of FIG. 106;
FIG. 111 is a front view of the design of FIG. 106;
FIG. 112 is a back view of the design of FIG. 106;
FIG. 113 is a perspective view of another embodiment of my new design of a toddler shoe with strap and heel pull;
FIG. 114 is a first side view of the design of FIG. 113;
FIG. 115 is a second side view of the design of FIG. 113;
FIG. 116 is a top view of the design of FIG. 113;
FIG. 117 is a bottom view of the design of FIG. 113;
FIG. 118 is a front view of the design of FIG. 113;
FIG. 119 is a back view of the design of FIG. 113;
FIG. 120 is a perspective view of another embodiment of my new design of a toddler shoe with strap and heel pull;
FIG. 121 is a first side view of the design of FIG. 120;
FIG. 122 is a second side view of the design of FIG. 120;
FIG. 123 is a top view of the design of FIG. 120;
FIG. 124 is a bottom view of the design of FIG. 120;
FIG. 125 is a front view of the design of FIG. 120;
FIG. 126 is a back view of the design of FIG. 120;
FIG. 127 is a perspective view of another embodiment of my new design of a toddler shoe with strap and heel pull;
FIG. 128 is a first side view of the design of FIG. 127;
FIG. 129 is a second side view of the design of FIG. 127;
FIG. 130 is a top view of the design of FIG. 127;
FIG. 131 is a bottom view of the design of FIG. 127;
FIG. 132 is a front view of the design of FIG. 127;
FIG. 133 is a back view of the design of FIG. 127;
FIG. 134 is a perspective view of another embodiment of my new design of a toddler shoe with strap and heel pull, in which the outpatch soles are hatched using the USPTO

convention of horizontal lines for blue (Pantone 277-Pantone 314, any one of Pantone 317-Pantone 320, Pantone 325 or Pantone 326, any one of Pantone 532-Pantone 552, any one of Pantone 628-Pantone 662, Pantone 801, Pantone 808, any one of Pantone 2702-Pantone 2708, Pantone 2717 or Pantone 2718, Pantone 2727 or Pantone 2728, Pantone 2747 or Pantone 2748, Pantone 2757 or Pantone 2758, Pantone 2767 or Pantone 2768, any one of Pantone 2905-Pantone 3165, any one of Pantone 3242-Pantone 3278, any one of Pantone 5395-Pantone 5435, any one of Pantone 7453-Pantone 7477, any one of Pantone 7541-Pantone 7547, or any one of RAL 5000-RAL 5026);

FIG. 135 is a first side view of the design of FIG. 134; FIG. 136 is a second side view of the design of FIG. 134; FIG. 137 is a top view of the design of FIG. 134; FIG. 138 is a bottom view of the design of FIG. 134; FIG. 139 is a front view of the design of FIG. 134; FIG. 140 is a back view of the design of FIG. 134; FIG. 141 is a perspective view of another embodiment of my new design of a toddler shoe with strap and heel pull; FIG. 142 is a first side view of the design of FIG. 141; FIG. 143 is a second side view of the design of FIG. 141; FIG. 144 is a top view of the design of FIG. 141; FIG. 145 is a bottom view of the design of FIG. 141; FIG. 146 is a front view of the design of FIG. 141; FIG. 147 is a back view of the design of FIG. 141; FIG. 148 is a perspective view of another embodiment of my new design of a toddler shoe with strap and heel pull; FIG. 149 is a first side view of the design of FIG. 148; FIG. 150 is a second side view of the design of FIG. 148; FIG. 151 is a top view of the design of FIG. 148; FIG. 152 is a bottom view of the design of FIG. 148; FIG. 153 is a front view of the design of FIG. 148; FIG. 154 is a back view of the design of FIG. 148; FIG. 155 is a perspective view of another embodiment of my new design of a toddler shoe with strap and heel pull; FIG. 156 is a first side view of the design of FIG. 155; FIG. 157 is a second side view of the design of FIG. 155; FIG. 158 is a top view of the design of FIG. 155; FIG. 159 is a bottom view of the design of FIG. 155; FIG. 160 is a front view of the design of FIG. 155; FIG. 161 is a back view of the design of FIG. 155; FIG. 162 is a perspective view of another embodiment of my new design of a toddler shoe with strap and heel pull; FIG. 163 is a first side view of the design of FIG. 162; FIG. 164 is a second side view of the design of FIG. 162; FIG. 165 is a top view of the design of FIG. 162; FIG. 166 is a bottom view of the design of FIG. 162; FIG. 167 is a front view of the design of FIG. 162; FIG. 168 is a back view of the design of FIG. 162; FIG. 169 is a perspective view of another embodiment of my new design of a toddler shoe with strap and heel pull; FIG. 170 is a first side view of the design of FIG. 169; FIG. 171 is a second side view of the design of FIG. 169; FIG. 172 is a top view of the design of FIG. 169; FIG. 173 is a bottom view of the design of FIG. 169; FIG. 174 is a front view of the design of FIG. 169; FIG. 175 is a back view of the design of FIG. 169; FIG. 176 is a perspective view of another embodiment of my new design of a toddler shoe with strap and heel pull, in which the outpatch soles are hatched using the USPTO convention of solid vertical lines for red or pink (Pantone 169-Pantone 171, any one of Pantone 176-Pantone 277, any one of Pantone 483-Pantone 485, any one of Pantone 490-Pantone 510, any one of Pantone 670-Pantone 680, any

one of Pantone 691-Pantone 711, Pantone 805 or Pantone 806, any one of Pantone 1765-Pantone 1955, any one of Pantone 2365-Pantone 2385, any one of Pantone 4985-Pantone 5035, or any one of RAL 3000-RAL 3033); FIG. 177 is a first side view of the design of FIG. 176; FIG. 178 is a second side view of the design of FIG. 176; FIG. 179 is a top view of the design of FIG. 176; FIG. 180 is a bottom view of the design of FIG. 176; FIG. 181 is a front view of the design of FIG. 176; FIG. 182 is a back view of the design of FIG. 176; FIG. 183 is a perspective view of another embodiment of my new design of a toddler shoe with strap and heel pull; FIG. 184 is a first side view of the design of FIG. 183; FIG. 185 is a second side view of the design of FIG. 183; FIG. 186 is a top view of the design of FIG. 183; FIG. 187 is a bottom view of the design of FIG. 183; FIG. 188 is a front view of the design of FIG. 183; FIG. 189 is a back view of the design of FIG. 183; FIG. 190 is a perspective view of another embodiment of my new design of a toddler shoe with strap and heel pull; FIG. 191 is a first side view of the design of FIG. 190; FIG. 192 is a second side view of the design of FIG. 190; FIG. 193 is a top view of the design of FIG. 190; FIG. 194 is a bottom view of the design of FIG. 190; FIG. 195 is a front view of the design of FIG. 190; FIG. 196 is a back view of the design of FIG. 190; FIG. 197 is a perspective view of another embodiment of my new design of a toddler shoe with strap and heel pull; FIG. 198 is a first side view of the design of FIG. 197; FIG. 199 is a second side view of the design of FIG. 197; FIG. 200 is a top view of the design of FIG. 197; FIG. 201 is a bottom view of the design of FIG. 197; FIG. 202 is a front view of the design of FIG. 197; FIG. 203 is a back view of the design of FIG. 197; FIG. 204 is a perspective view of another embodiment of my new design of a toddler shoe with strap and heel pull; FIG. 205 is a first side view of the design of FIG. 204; FIG. 206 is a second side view of the design of FIG. 204; FIG. 207 is a top view of the design of FIG. 204; FIG. 208 is a bottom view of the design of FIG. 204; FIG. 209 is a front view of the design of FIG. 204; FIG. 210 is a back view of the design of FIG. 204; FIG. 211 is a perspective view of another embodiment of my new design of a toddler shoe with strap and heel pull; FIG. 212 is a first side view of the design of FIG. 211; FIG. 213 is a second side view of the design of FIG. 211; FIG. 214 is a top view of the design of FIG. 211; FIG. 215 is a bottom view of the design of FIG. 211; FIG. 216 is a front view of the design of FIG. 211; FIG. 217 is a back view of the design of FIG. 211; FIG. 218 is a perspective view of another embodiment of my new design of a toddler shoe with strap and heel pull, in which the outpatch soles are hatched using the USPTO convention of vertical and horizontal cross-hatched lines for yellow or gold (Pantone 100-Pantone 147, Pantone 155, Pantone 379 or Pantone 380, any one of Pantone 386-Pantone 388, any one of Pantone 393-Pantone 399, any one of Pantone 454-Pantone 461, any one of Pantone 585-Pantone 620, Pantone 803, Pantone 809 or Pantone 810, any one of Pantone 3935-Pantone 3985, or any one of RAL 1000-RAL 1037); FIG. 219 is a first side view of the design of FIG. 218; FIG. 220 is a second side view of the design of FIG. 218; FIG. 221 is a top view of the design of FIG. 218; FIG. 222 is a bottom view of the design of FIG. 218;

FIG. 223 is a front view of the design of FIG. 218;
FIG. 224 is a back view of the design of FIG. 218;
FIG. 225 is a perspective view of another embodiment of my
new design of a toddler shoe with strap and heel pull;
FIG. 226 is a first side view of the design of FIG. 225;
FIG. 227 is a second side view of the design of FIG. 225;
FIG. 228 is a top view of the design of FIG. 225;
FIG. 229 is a bottom view of the design of FIG. 225;
FIG. 230 is a front view of the design of FIG. 225;
FIG. 231 is a back view of the design of FIG. 225;
FIG. 232 is a perspective view of another embodiment of my
new design of a toddler shoe with strap and heel pull;
FIG. 233 is a first side view of the design of FIG. 232;
FIG. 234 is a second side view of the design of FIG. 232;
FIG. 235 is a top view of the design of FIG. 232;
FIG. 236 is a bottom view of the design of FIG. 232;
FIG. 237 is a front view of the design of FIG. 232;
FIG. 238 is a back view of the design of FIG. 232;
FIG. 239 is a perspective view of another embodiment of my
new design of a toddler shoe with strap and heel pull;
FIG. 240 is a first side view of the design of FIG. 239;
FIG. 241 is a second side view of the design of FIG. 239;
FIG. 242 is a top view of the design of FIG. 239;
FIG. 243 is a bottom view of the design of FIG. 239;

FIG. 244 is a front view of the design of FIG. 239;
FIG. 245 is a back view of the design of FIG. 239;
FIG. 246 is a perspective view of another embodiment of my
new design of a toddler shoe with strap and heel pull;
FIG. 247 is a first side view of the design of FIG. 246;
FIG. 248 is a second side view of the design of FIG. 246;
FIG. 249 is a top view of the design of FIG. 246;
FIG. 250 is a bottom view of the design of FIG. 246;
FIG. 251 is a front view of the design of FIG. 246;
FIG. 252 is a back view of the design of FIG. 246;
FIG. 253 is a perspective view of another embodiment of my
new design of a toddler shoe with strap and heel pull;
FIG. 254 is a first side view of the design of FIG. 253;
FIG. 255 is a second side view of the design of FIG. 253;
FIG. 256 is a top view of the design of FIG. 253;
FIG. 257 is a bottom view of the design of FIG. 253;
FIG. 258 is a front view of the design of FIG. 253; and,
FIG. 259 is a back view of the design of FIG. 253.
The dotted lines represents stitching, which do not form a
part of the claimed design.
The wavy lines represent surface shading.
